F. L. SCRymgeour,
ATTACHMENT FOR FORMING A FRENCH EDGE ON VELVET HATS.
APPLICATION FILED JULY 28, 1915.

1,164,126.

Patented Dec. 14, 1915.

UNITED STATES PATENT OFFICE.

FRANK L. SCRYMGEOUR, OF MANSFIELD, MASSACHUSETTS.

ATTACHMENT FOR FORMING A FRENCH EDGE ON VELVET HATS.

1,164,126.

Specification of Letters Patent. Patented Dec. 14, 1915.

Application filed July 28, 1915. Serial No. 42,405.

To all whom it may concern:

Be it known that I, FRANK L. SCRYMGEOUR, a citizen of the United States, residing at Mansfield, county of Bristol, State 5 of Massachusetts, have invented a certain new and useful Improvement in Attachments for Forming a French Edge on Velvet Hats, of which the following is a specification, reference being had therein to the accompanying drawings.

The invention relates to a device for forming a so-called "French" edge or "cigarette" edge on velvet hats.

In the manufacture of velvet hats the 15 rim is usually composed of three layers of fabric, namely, a top and bottom layer of velvet and an intermediate layer of buckram or similar stiffening material, and frequently also the edge is wired. In 20 the manufacture of the so-called "French" edge the upper layer of velvet and the intermediate layer of buckram are cut back for a short distance from the edge of the lower layer of velvet all the way around 25 so that the lower layer of velvet projects out beyond the upper layer of velvet and the buckram for a sufficient distance, say perhaps about five-sixteenths of an inch, so that when the wire is laid upon the upper 30 surface of the velvet near the edge, the said projecting portion or flange of the lower layer of velvet may be rolled over around the wire to form a bead. It is usual to apply an adhesive to the wire and to the upper 35 face of said projecting rim of velvet before the velvet is rolled around the wire so that when the velvet is rolled about the wire the two adhesive surfaces will come together and firmly cement the wire and the velvet 40 together. In order to make a more nicely finished edge it is important that when the said flange of velvet is rolled over around the wire the edge shall be turned in under the wire so that the edge will be out of sight 45 and make a more finished appearance to the roll. It is difficult and expensive to do this by hand and it is also expensive to make a complete machine especially for that purpose.

The object of the present invention is to 50 provide a device by which the folded flange of velvet will be properly rolled around the wire and tucked in and it is also the object of the invention to provide a device of such 55 a character that it can be readily attached

to an ordinary hat sewing machine, such for instance as a Wilcox and Gibbs, or any one of a number of other makes of sewing machines on the market, and thereby to utilize a machine already on hand which when desired can be used as a sewing machine and which is readily adapted for use to form the "French" edge and in which also the sewing machine feed will be utilized to feed the hat while forming the "French" edge. 60

The invention will be fully understood from the following description when taken in connection with the accompanying drawings and the novel features thereof will be pointed out and clearly defined in the claims 70 at the close of this specification.

In the drawings,—Figure 1 is a side elevation of a device embodying the invention attached to the foot bar of a sewing machine of the Wilcox and Gibbs type, the needle 75 bar being removed and portions of the machine being broken away which are not necessary to illustrate the invention. Fig. 2 is a side elevation of the device embodying the invention detached from the machine. Fig. 3 is a plan view of a portion of a hat brim showing the wire in place and a portion of the flange of the lower layer of velvet turned over as it should be before application to the machine, a portion of the velvet flange being 80 shown as it is before it is doubled over in order to show the location of the wire. Fig. 4 is a section enlarged on line 4—4 of Fig. 3. Fig. 5 is a plan view of a portion of a hat brim and of the device embodying the 90 invention applied thereto as in operation, the machine being omitted. Fig. 6 is a section on line 6—6 of Fig. 5 showing the position of the parts in the operation of forming the "French" edge. Fig. 7 is a plan 95 view on an enlarged scale of the toothed grooved wheel which engages and tucks in the velvet around the wire.

Referring now to the drawings, the body of the device, which may be of a single 100 block of metal, has a head portion 1, and a foot portion 2 which is curled up at the end forming an overhanging arm 3 which has a slot 4 whereby it may be connected with the foot bar 5 of a sewing machine. The 105 foot bar 5 passes through the slot 4 and the device is secured to the foot bar by a nut 6 and washer 7 in the same way that the foot of a sewing machine is connected with the foot bar. In side elevation view the 110

part thus far described closely resembles the foot of a sewing machine. The head 1 is under cut so that the foot portion 2 projects down lower than the under side of the 5 head 1.

A grooved roll 10 is mounted on a pin 8 which extends up through the head 1 of the device. Said pin is secured and clamped therein by a set screw 9, said roll 10 having 10 a groove 11 which is somewhat like the groove of a pulley wheel, and which is of sufficient diameter to receive the wire with its velvet covering. The thin flange 12 which forms the lower end of the roll is preferably 15 toothed on its periphery as clearly shown in Fig. 7, and the lower face of this flange should preferably be at substantially the same level as the lower face of the foot 2. Secured to the upper side of the head 1 is a 20 spring presser member 13 whose under face is also on about the same level as the lower face of the flange 12 of the grooved roll. The under face of the foot 2 is formed with a longitudinal groove 19 to afford clearance 25 for the covered wire.

When the device is attached to a sewing machine as in Fig. 1, the needle bar should be removed as it is not used in the wiring operation and it would extend down into the 30 way of the tucking device during the operation of the machine. The feed 14 is the toothed feed of the sewing machine of ordinary form and is actuated in well known manner which does not require description.

35 The brim of the hat to be wired has three layers of fabric, as already mentioned, and as shown in Figs. 3, 4 and 6, namely, a bottom layer 15 of velvet, a top layer 16 of velvet and an intermediate layer 17 of buckram. 40 The top layer of velvet 16 and the layer of buckram 17 are both cut back for a short distance as clearly shown in Fig. 3 exposing a flange portion of the lower layer of velvet 15 which extends all around the rim. Cement 45 is applied to the upper face of this exposed portion, then the wire 18 is put in position on top of the upper layer of velvet, near the edge, and extending entirely around the rim and is also treated with cement. Then 50 the flange of the lower layer of velvet 15 is by hand or by other suitable means turned over the wire as shown in Fig. 4. In Fig. 3 it is shown turned over part way of its length but it should be turned over all the 55 way around before starting it in the machine. The cement will temporarily hold it in this position until the grooved tucker acts upon it. The meeting ends of the wire are clasped together as shown in Fig. 5 at 20, 60 to more surely hold the ends from spreading apart. The hat is then ready to be introduced into the machine as shown in Fig. 6, positioning it in such manner that the flange 12 of the roller 10 will engage the turned 65 over portion of the flange of the lower layer

of velvet and tuck it in under the wire as shown in said Fig. 6. The spring presser 13 will rest on the upper surface of the turned over flange 15 in advance of the roller 10. Now when the machine is started 70 the feed 14 will move the hat which should be held by the operator and guided, and as it travels the flange 12 of the roll 10 will tuck in the turned over flange of the lower layer of velvet 15 all the way around the 75 hat. The roll 10 is revoluble on the pin 8. A grooved stationary guide might be employed, but it is better to have the guide in form of a roll or wheel and revoluble. 80

What I claim is:

1. An attachment for a machine for tucking in the covering of the edge wire of a hat brim comprising a body portion, and a peripherally grooved roller mounted thereon, the axis of the roller being perpendicular to the plane of the feed, the groove of said roller being adapted to receive the covered wire, said roller having a flange which is adapted to engage the turned over portion of the covering for the wire and tuck it in 90 under the wire.

2. An attachment for a machine for tucking in the covering of the edge wire of a hat brim, said attachment comprising a body portion, and a grooved roller mounted thereon, the axis of rotation of the roller being perpendicular to the plane of the feed of the hat brim, the roller being formed with a circumferential groove which is adapted to receive the covered wire, said roller having a flange which forms the lower edge of the groove and is adapted to engage the turned over portion of the covering for the wire and tuck it in under the wire, said device being formed with a foot whereby it 105 may be attached to a machine.

3. An attachment for a machine for tucking in the covering of the edge wire of a hat brim comprising a body portion, a grooved roller mounted thereon, the groove of said roller being adapted to receive the covered wire, said roller having a flange which is adapted to engage the turned over portion of the covering and tuck it under the wire, said device being formed with a foot portion 110 whereby it may be attached to a machine, and a spring presser member secured to the body of said device in a position to engage the turned over portion of the covering in advance of the engagement of the said roll 120 with the said wire and its covering.

4. An attachment for a machine for tucking in the covering of the edge wire of a hat brim, said attachment comprising a body portion, and a grooved roller mounted 125 thereon, the groove of said roller being adapted to receive the covered wire, said roller having a flange which is adapted to engage the turned over portion of the covering for the wire and tuck it in under the 130

wire, said device being formed with a foot formed with a longitudinal groove in its under side to afford clearance for the roll formed by the covered wire.

5. In combination with the foot bar of a sewing machine, an attachment for tucking in the covering of the edge wire of a hat brim, said attachment comprising a body portion, and a peripherally grooved roller 10 mounted thereon, the axis of the roller being perpendicular to the plane of travel of the hat brim, the groove of said roller being adapted to receive the covered wire, said roller having a flange parallel with the 15 plane of travel of the hat brim which is adapted to engage the turned over portion of the covering for the wire and tuck it in under the wire.

6. In combination with a machine having 20 a foot bar and a feed, an attachment for tucking in the covering of the edge wire of a hat brim, said attachment comprising a body portion, and a peripherally grooved roller mounted thereon, the axis of the roller 25 being vertical and the groove of said roller being adapted to receive the covered wire, said roller having a peripheral flange bordering the lower side of the groove which is adapted to engage the turned over portion 30 of the covering for the wire and tuck it in under the wire.

7. In combination with a foot bar and feed of a sewing machine, an attachment for forming a "French" edge on a velvet hat, 35 said attachment comprising a body portion having a foot constructed and arranged for attachment to said foot bar, and a peripherally grooved roller mounted on said body portion the axis of the roller being perpendicular to the plane of travel of the hat brim, said roller having a horizontal flange at the lower end and being so positioned that the groove of said roller is adapted to receive the wire and its covering of velvet, 45 and said flange being adapted to engage and tuck the edge of the velvet beneath the wire while the hat is being moved by the feed.

8. In combination with a foot bar and feed of a sewing machine, an attachment for 50 forming a "French" edge on a velvet hat, said attachment comprising a body portion having a foot constructed and arranged for attachment to said foot bar, a grooved roller mounted on said body portion, said roller 55 having a flange at one end and being so positioned that the groove of said roller is adapted to receive the wire and its covering of velvet, and said flange being adapted to engage and tuck the edge of the velvet beneath the wire while the hat is being moved by the feed, and a spring presser member mounted on said body which engages the turned over portion of the hat brim in advance of the engagement of the grooved 60 roll with the wire.

9. In combination with a machine having a cloth feed, and a foot bar, an attachment for tucking in under the wire of a hat brim the turned over edge of the brim, said attachment comprising a body portion, a foot 70 portion having a toe turned up and then backward and slotted for attachment to the foot bar, and a grooved roll revolvably mounted on a vertical axis on the under side of said body, said roll having a circumferential groove and a thin horizontal flange on the under side which engages with a turned over edge of the hat brim and tucks it in under the wire while the hat is being moved by the said feed. 75

10. In combination with a machine having a cloth feed, and a foot bar, an attachment for tucking in under the wire of a hat brim the turned over edge of the brim, said attachment comprising a body portion, a 80 foot portion constructed for attachment to the foot bar, and a grooved roll revolvably mounted on a vertical axis on the under side of said body, said roll having a circumferential groove and a thin horizontal flange on the under side which engages with a turned over edge of the hat brim and tucks it in under the wire while the hat is being moved by the said feed, said flange for the 85 roller being formed with teeth in its periphery. 90

11. In combination with a machine having a cloth feed, and a foot bar, an attachment for tucking in under the wire of a hat brim the turned over edge of the brim, said 100 attachment comprising a body portion, a foot portion constructed for attachment to the foot bar, a grooved roll revolvably mounted on the under side of said body, said roll having a circumferential groove and a thin flange on the under side which engages with a turned over edge of the hat brim and tucks it in under the wire while the hat is being moved by the said feed, said flange for the 105 roller being formed with teeth in its periphery, and a spring presser secured to said body in a position to engage the hat brim in advance of its engagement by the said grooved roll. 110

12. A device to be attached to a machine for covering the edge wire of a hat brim, said device comprising a body portion, a roller rotatively mounted on the under side of said body on a vertical stud, said roller being formed with a circumferential groove 115 adapted to receive the covered wire, a horizontal flange on the lower end of said roller, a presser member secured to said body and extending rearwardly thereof and having a horizontal base portion which is in the same plane as the flange of said roller, and a forwardly extending foot portion attached to said body, the bottom of said foot being in the same horizontal plane as said flange. 120 125

13. In combination with a machine having a foot bar, and a feed, an attachment for tucking in the covering of the edge wire of a hat brim, said attachment comprising a body portion, a roller rotatably mounted on the under side of said body on a vertical stud, said roller being formed with a circumferential groove adapted to receive the covered wire, a horizontal flange on the lower end of said roller, a presser member secured to said body and extending rearwardly thereof and having a horizontal base portion which is in the same plane as the flange of said roller, and a forwardly extending foot portion attached to said body, the bottom of said foot being in the same horizontal plane as said flange.
14. In combination with a machine having a foot bar, an attachment to the foot bar for tucking in the covering of the edge wire of a hat brim, said attachment comprising a body portion, a roller rotatably mounted on the under side of said body and rotatable on a vertical axis, said roller being formed with a circumferential groove, a horizontal circular flange on the lower end of said roller, and a feed located and movable in a plane parallel with and below the said flange on the roller.
15. In combination with a machine having a foot bar, an attachment for said foot bar, said attachment comprising a body portion, a roller rotatably mounted on the under side of said body and rotatable on a vertical axis, said roller being formed with a circumferential groove, a horizontal circular flange on the lower end of said roller, said flange being formed with teeth in its periphery, and means for attaching said device to said foot bar.
16. In combination with a machine having a foot bar, an attachment for said foot bar, said attachment comprising a body portion, a roller rotatably mounted on the under side of said body and rotatable on a vertical axis, said roller being formed with a circumferential groove, a horizontal circular flange on the lower end of said roller, said flange being formed with teeth in its periphery, and means for attaching said device to said foot bar, and a horizontally movable feed located in a plane below the said grooved roll.
17. In combination with a machine having a foot bar, an attachment for said foot bar for tucking in the covering of the edge wire of a hat brim, said attachment comprising a body portion having a horizontal groove in one side thereof to receive and guide the covered wire, a horizontal flange below said groove adapted to engage and tuck in the covering of the wire, a presser member in the rear of said flange, a foot in front of said flange, the bottom of said presser member, said flange and said foot all being in substantially the same horizontal plane and a feed movable in a plane below and parallel with the plane of the bottom of said flange.

In testimony whereof I affix my signature, 70
in presence of two witnesses.

FRANK L. SCRYMGEOUR.
